UNITED STATES PATENT OFFICE.

ELLIOTT G. THORP, OF BOSTON, MASSACHUSETTS.

DESIGN FOR AN ALBUM-LEAF.

SPECIFICATION forming part of Design No. 19,831, dated May 6, 1890.

Application filed March 27, 1890. Serial No. 345,767. Term of patent 3½ years.

To all whom it may concern:

Be it known that I, ELLIOTT G. THORP, of Boston, county of Suffolk, and State of Massachusetts, have invented and produced a new and original Design for Photographic Album Leaves, of which the following is a specification, reference being had to the accompanying drawing, forming part thereof.

The drawing shows a leaf embodying my design.

The leading feature of my design consists in a leaf for a photographic album or book having an irregular hexagonal outline or contour.

Referring by letter to the drawing, A designates an album or book leaf having the an-

gle sides a and the shorter sides a' . Two of the opposite or parallel sides a are shown as somewhat shorter than the other two opposite or parallel sides a , and the short sides a' are substantially parallel one with the other. The usual picture-space a^2 is provided in the leaf. Either one of the sides a or a' may be attached to a binding.

What I claim is—

The design for a book or album leaf, substantially as herein shown and described.

ELLIOTT G. THORP.
